(57) **CLAIM**

The ornamental design for a shoe as shown and described.

DESCRIPTION

FIG. 1 is a front perspective view of a shoe in accordance with our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dashed broken lines define the boundaries of the upper, midsole, and outsole and form no part of the claimed design. The dashed broken lines surrounding the whited out portions, along with the whited out portions, form no part of the claimed design.

1 Claim, 7 Drawing Sheets
